CLAIM

We claim, the ornamental design for the kick-stand pad, as shown and described.

DESCRIPTION

FIG. 1 is a front elevational view of the kick-stand pad showing my new design;

FIG. 2 is a left-side elevational view of the kick-stand pad thereof;

FIG. 3 is a top plan view of the kick-stand pad thereof;

FIG. 4 is a bottom plan view of the kick-stand pad thereof; and,

FIG. 5 is a perspective view of the kick-stand pad thereof. The broken lines showing a portion of a kick stand form no part of the claimed design.
